J. HUNTER.
SIDE OF A FULLING-MILL CASE

No. D7,982

Patented January 5, 1875

Fig. 1

Fig. 2

UNITED STATES PATENT OFFICE.

JAMES E. HUNTER, OF NORTH ADAMS, MASSACHUSETTS.

DESIGN FOR THE SIDE OF A FULLING-MILL CASE.

Specification forming part of Design No. 7,982, dated January 5, 1875; application filed March 21, 1874.
(Term of Patent 7 years.)

To all whom it may concern:

Be it known that I, JAMES E. HUNTER, of North Adams, in the county of Berkshire and State of Massachusetts, have invented a new and original Design for the Side of a Fulling-Mill Case, of which the following is a specification:

The drawing represents an elevation of the side of the mill-frame or casing.

Similar letters of reference indicate corresponding parts.

My design consists of the side of the case

in three separate and distinct parts, A B C, constructed in the form represented in the drawing, and comprising the full or complete side.

I claim as my invention—

The design for the side of a fulling-mill case, composed of the three parts A B C, having the form shown.

JAMES E. HUNTER.
